UNITED STATES PATENT OFFICE.

EDWARD A. FIELD AND EDWARD A. FIELD, JR., OF CHICAGO, ILLINOIS, ASSIGNEES,
BY MESNE ASSIGNMENTS, TO EDWARD A. FIELD, OF CHICAGO, ILLINOIS.

LIQUID-FUEL-FEED DEVICE.

Application filed November 10, 1924. Serial No. 748,940.

This invention relates to improvements in liquid fuel feed devices.

Our improved liquid fuel feed device is especially designed by us for the maintaining of a substantially constant supply of fuel in a gravity feed tank for liquid fuel burners such, for instance, as shown in our application for Letters Patent filed June 25, 1923, Serial No. 647,657, and while we have designed our feed device especially for use with the burner as shown therein, it will be understood that it is adapted for use with any type of liquid fuel feed device where the fuel is supplied directly to the burner by gravity as distinguished from a pressure feed.

The main objects of the invention are:

First, to provide an improved feed device of the class described in which a substantially constant supply of fuel is maintained in the gravity feed tank, drawing the same from a storage or supply tank.

Second, to provide an improved feed device having these advantages which is automatically operated.

Third, to provide an improved liquid fuel feed device which is simple in its parts and not likely to become inoperative in use.

Further objects, and objects relating to structural details, will definitely appear from the detailed description to follow.

We accomplish the objects of our invention by the devices and means described in the following specification. The invention is clearly defined and pointed out in the claims.

A structure which is a preferred embodiment of our invention is clearly illustrated in the accompanying drawing, forming a part of this application, in which:

Fig. I is a perspective view of a fuel feed equipment embodying the features of our invention, the illustration being largely conventionalized and no attempt being made to maintain the parts in their relative proportions, it being intended only to show their operative relation.

Fig. II is a detail view mainly in vertical central section through the feed control mechanism.

Fig. III is a perspective view of the bottom plate of the fuel control mechanism with the parts mounted thereon.

In the drawing similar reference characters refer to similar parts throughout the several

views. The parts will be referred to by their numbers.

Referring to the drawing, 1 represents a furnace; 2 the fuel storage or supply tank and 3 the fuel feed tank which is connected to the furnace by the pipe 4 to deliver by gravity to the furnace burner not illustrated.

We provide an ejector indicated at 5, the ejector having a water supply connection 6 and a water delivery connection 7. This water supply connection may be any suitable source of water supply as the water supply system of a residence.

The vacuum tank 8 is closed at its upper end, being flanged at 9 at its lower end to receive the screws 10 for attaching the bottom plate 11 thereto. A gasket 12 is arranged between the flange 9 and the bottom plate so that the tank is sealed except for the connections to be described.

Within this tank 8 is an inverted bucket or float 13. The air suction pipe 14 of the ejector 5 has an upright terminal 15 projecting into the vacuum tank and opening well toward the top of the float 13. On the upper end of this suction pipe terminal 15 is an upwardly facing valve seat 16. A conical valve 17 is mounted upon the float to coact with this valve seat so that when the float is in its lowest position, the suction pipe is closed, but when open the suction pipe is open so that air is drawn from the vacuum chamber or tank 85 by the ejector.

On the bottom plate 11 is a supporting block 18 having upwardly projecting ears 19 to which the arm 20 of the counterweight 21 is pivoted. The outer end of this arm is 90 pivotally connected at 22 to the downwardly projecting arm 23 carried by a cross piece 24 within the float. This connection serves the double purpose of a counterweight for the float and a guiding means for the lower end 95 thereof.

The float chamber is connected to the fuel supply tank 2 by means of the intake pipe 25, a return check valve 26 for this pipe being mounted on the bottom plate 11.

The vacuum tank or chamber is connected by the discharge pipe 27 to the gravity feed tank 3. The bottom plate 11 has a downwardly facing inclined valve seat 28 for the downwardly opening discharge valve 29 of the 105 discharge pipe 27. This discharge valve 29

has a stem 30 reciprocating in the supporting block 18 and connected to the arm 23 on the float by the link 31 so that when the float falls the valve 29 is opened and the fuel 5 within the tank 8 is discharged to the feed tank. The pipe 27 is of greater capacity than the valve 29 so that it serves as an air return pipe as well as a fuel discharge pipe. The valve seat 28 being inclined permits the fuel 10 to flow down in the bottom part of the valve while the air passes up at the upper side 15 or edge of the valve.

An air guide conduit 32 is provided for 15 guiding the air passing the valve to the outside of the float. The action of the device is intermittent, a cycle of operation being as follows:

The discharge valve will be held closed by 20 the counterweight and the float will be held in its elevated position consequently the suction valve 17 will be open. The suction produced by the ejector is effective within the 25 vacuum tank and oil rises from the main storage tank past the check valve 26 and fills the lower part of the tank up to the lower edge 30 of the float. Its further rise is only within the float as the suction continues to exhaust the air from the float. This suction acts on the oil discharge valve, holding it closed until 35 the oil rises to a height in the float sufficient to over-balance the counterweight and discharge valve by the effective weight of the float when the float will drop, closing the suction valve 17 and opening the discharge valve, and 40 the oil flows out of the discharge valve and the air enters through the same as described. In operation the liquid does not rise in tank 8 much above the lower level of the bucket because the vacuum is not affected after the 45 tank is sealed by this liquid. The liquid, however, continues to rise inside the floater bucket until the weight of the bucket and the liquid overcomes the differential of the counterweight and atmosphere on the outside of the 50 valve 29. When the counterweight is raised, the vacuum connection is shut off, permitting the liquid to discharge when another cycle of operation will take place. The fuel is thus discharged from the vacuum tank and 55 during this operation a high vacuum is formed in the pipe 14 between the vacuum tank and ejector, thus insuring a quick action at the start of the next cycle resulting in economy of water. When the float has emptied to 60 the predetermined point, the counterweight overbalances the float and closes the discharge valve. When open, the vacuum is not effective on the discharge valve, but when it closes the vacuum is again effective and another 65 cycle begins.

To prevent waste of water and also to maintain substantially constant level of fuel in the feed tank, we provide the water supply pipe 6 with a valve 33 operatively connected to the 70 float 34 within the feed valve by means of the

connection designated generally by the numeral 35. We have not detailed the valve 33 or the float and connections as these parts will be considerably varied according to the particular installation.

We have illustrated and described our improvements in an embodiment which we have found very satisfactory, the same, as stated, being especially designed for maintaining a supply of fuel in a gravity feed tank from 75 a liquid supply or storage tank.

We have not attempted to illustrate or describe certain modifications and adaptations which we contemplate as we believe the disclosure made will enable those skilled in the 80 art to embody or adopt our improvements as may be desired.

Having thus described our invention, what we claim as new and desire to secure by Letters Patent is:

1. In a structure of the class described, the combination of a delivery tank, a vacuum tank, an inverted float disposed in said vacuum tank, a suction pipe projecting into said vacuum tank within said float, said suction pipe having an upwardly facing valve seat at its upper end, a coacting valve carried by said float and provided with a pilot stem projecting through the valve seat whereby the upper end of the float is guided, a counterweight pivotally mounted within said vacuum tank and pivotally connected to said float, an intake connection for said vacuum tank below said float, a return check valve for said intake connection, a discharge valve having a downwardly facing inclined valve seat and provided with an upwardly projecting supporting and guiding stem, a link connecting said discharge valve stem to said float, a conduit connecting said discharge valve to said delivery tank, the capacity of the conduit exceeding that of the valve so that the conduit serves as a liquid discharge and air return conduit, and an air conduit opening at the upper side of said discharge valve and discharging into said vacuum tank at the outside of said float.

2. In a structure of the class described, the combination of a delivery tank, a vacuum tank, an inverted float disposed in said vacuum tank, a suction pipe projecting into said vacuum tank within said float, said suction pipe having an upwardly facing valve seat at its upper end, a coacting valve carried by said float, a counterweight operatively connected to said float, an intake connection for said vacuum tank below said float, a return check valve for said intake connection, a discharge valve having a downwardly facing inclined valve seat and provided with an upwardly projecting supporting and guiding stem, a link connecting said discharge valve stem to said float, a conduit connecting said discharge valve to said delivery tank, the capacity of the conduit exceeding that of the 130

valve so that the conduit serves as a liquid discharge and air return conduit, and an air conduit opening at the upper side of said discharge valve and discharging into said vacuum tank at the outside of said float.

3. In a structure of the class described, the combination of a delivery tank, a vacuum tank, an inverted float disposed in said vacuum tank, a suction pipe projecting into said vacuum tank within said float, said suction pipe having an upwardly facing valve seat at its upper end, a coacting valve carried by said float and provided with a pilot stem projecting through the valve seat whereby the upper end of the float is guided, a counterweight pivotally mounted within said vacuum tank and pivotally connected to said float, an intake connection for said vacuum tank below said float, a return check valve for said intake connection, a discharge valve having a downwardly facing inclined valve seat and provided with an upwardly projecting supporting and guiding stem, a link connecting said discharge valve stem to said float, and a conduit connecting said discharge valve

stem to said delivery tank, the capacity of the conduit exceeding that of the valve so that the conduit serves as a liquid discharge and air return conduit.

4. In a structure of the class described, the combination of a delivery tank, a vacuum tank, an inverted float disposed in said vacuum tank, a suction pipe projecting into said vacuum tank within said float, said suction pipe having an upwardly facing valve seat at its upper end, a coacting valve carried by said float, a counterweight operatively connected to said float, an intake connection for said vacuum tank below said float, a return check valve for said intake connection, a discharge valve having a downwardly facing inclined valve seat and provided with an upwardly projecting supporting and guiding stem, a link connecting said discharge valve stem to said float, and a conduit connecting said discharge valve to said delivery tank, the capacity of the conduit exceeding that of the valve so that the conduit serves as a liquid discharge and air return conduit.

5. In a structure of the class described, the combination of a delivery tank, a vacuum tank, an inverted float disposed in said vacuum tank, a suction connection to said vacuum tank opening within said float, a valve for said suction connection actuated by said float, a counterweight operatively connected to said float, an intake connection for said vacuum tank below said float, a return check valve for said intake connection, a discharge valve having a downwardly facing inclined valve seat and provided with an upwardly projecting supporting and guiding stem, a link connecting said discharge valve stem to said float, a conduit connecting said discharge valve to said delivery tank,

the capacity of the conduit exceeding that of the valve so that the conduit serves as a liquid discharge and air return conduit, and an air conduit opening at the upper side of said discharge valve and discharging into said vacuum tank at the outside of said float.

6. In a structure of the class described, the combination of a delivery tank, a vacuum tank, an inverted float disposed in said vacuum tank, a suction connection to said vacuum tank opening within said float, a valve for said suction connection actuated by said float, a counterweight operatively connected to said float, an intake connection for said vacuum tank below said float, a return check valve for said intake connection, a discharge valve having a downwardly facing inclined valve seat and provided with an upwardly projecting supporting and guiding stem, a link connecting said discharge valve stem to said float, and a conduit connecting said discharge valve to said delivery tank, the capacity of the conduit exceeding that of the valve so that the conduit serves as a liquid discharge and air return conduit.

7. In a structure of the class described, the combination of a delivery tank, a vacuum tank, an inverted float disposed in said vacuum tank, a suction pipe projecting into said vacuum tank within said float, said suction pipe having an upwardly facing valve seat at its upper end, a coacting valve carried by said float and provided with a pilot stem projecting through the valve seat whereby the upper end of the float is guided, a counterweight pivotally mounted within said vacuum tank and pivotally connected to said float, an intake connection for said vacuum tank provided with a return check valve, a discharge valve operatively connected to said float, and a conduit connecting said discharge valve to said delivery tank, the capacity of the conduit exceeding that of the valve so that the conduit serves as a liquid discharge and air return conduit.

8. In a structure of the class described, the combination of a delivery tank, a vacuum tank, an inverted float disposed in said vacuum tank, a suction pipe projecting into said vacuum tank within said float, said suction pipe having an upwardly facing valve seat at its upper end, a coacting valve carried by said float, an intake connection for said vacuum tank provided with a return check valve, a discharge valve operatively connected to said float, and a conduit connecting said discharge valve to said delivery tank, the capacity of the conduit exceeding that of the valve so that the conduit serves as a liquid discharge and air return conduit.

9. In a structure of the class described, the combination of a delivery tank, a vacuum tank, an inverted float disposed in said vacuum tank, a suction connection to said vacuum

tank opening within said float, a valve for said suction connection actuated by said float, a counterweight operatively connected to said float, an intake connection to the bottom 5 of said vacuum tank below said float, a return check valve for said intake connection, a discharge valve operatively connected to said float, and a conduit connecting said discharge valve to said delivery tank, the capacity of 10 the conduit exceeding that of the valve so that the conduit serves as a liquid discharge and air return conduit.

10. In a structure of the class described, the combination of a delivery tank, a vacuum 15 tank, an inverted float disposed in said vacuum tank, a suction connection to said vacuum tank opening within said float, a valve for said suction connection actuated by said float, an intake connection to said vacuum tank 20 below said float, a return check valve for said intake connection, a discharge valve oper-

atively connected to said float, and a conduit connecting said discharge valve to said delivery tank, the capacity of the conduit exceeding that of the valve so that the conduit 25 serves as a liquid discharge and air return conduit.

11. In a structure of the class described, the combination of a delivery tank, a vacuum 30 tank, an inverted float disposed in said vacuum tank, a suction connection to said vacuum tank opening within said float, a valve for said suction connection actuated by said float, an intake connection for said vacuum tank below said float, a return check valve for 35 said intake connection, and a discharge valve operatively connected to said float.

In witness whereof we have hereunto set our hands.

EDWARD A. FIELD.
